TYPEWRITING MACHINE

Charles H. Beiderbecke, Lyons, N. Y., assignor
to International Business Machines Corpora-
tion, New York, N. Y., a corporation of New
York

Application June 22, 1938, Serial No. 215,110

15 Claims. (Cl. 197—126)

This invention relates to continuous billing machines.

The broad object of the present invention is to improve continuous billing machines.

5 An object is to provide a billing machine in which the carriage of the typewriting machine is relieved of the weight of the forms carrier and carbon sheet controlling device.

Another object is to provide a forms carrier 10 which is relatively simple in construction and operated by foot power thereby relieving the operator's hands of much of the work ordinarily required to effect a displacement of the carbon sheets relative to the forms.

15 An object is to provide an improved platen displacing mechanism.

Another object is to provide means to prevent displacement of the platen to non-typing position except when the carriage has been aligned 20 with the forms carrier.

An object is to provide means to automatically bring the carriage into alignment with the forms carrier.

25 Another object is to provide a forms carrier adapted to use carbon sheets in roll form whereby the pack of continuous forms may be kept supplied with fresh carbon sheets without re-threading the forms except at relatively long intervals.

30 Further objects of the instant invention reside in any novel feature of construction or operation or novel combination of parts present in the embodiment of the accompanying drawings whether within or without the scope of the appended 35 claims and irrespective of other specific statements as to the scope of the invention contained herein.

In the drawings:

Fig. 1 is a plan view of the machine;

40 Fig. 2 is a vertical section substantially on the line 2—2 of Fig. 1;

Fig. 3 is a large scale plan view of the forms carrier;

Fig. 4 is a rear elevation of the carbon roll carriers.

45 Fig. 5 is a front elevation of one of the carbon roll carriers;

Fig. 6 is a large scale rear view of the partial carriage return mechanism;

50 Fig. 7 is a large scale elevation of the right hand end of the carriage with reference to Fig. 1;

Fig. 8 is a large scale vertical section substantially on line 8—8 in Fig. 1;

55 Fig. 9 is a perspective diagrammatic view of the carriage return mechanism;

Fig. 10 is a detail view of the knife supporting arms and latch mechanism therefor;

Fig. 11 is a large scale vertical section on the line 11—11 in Fig. 1;

Fig. 12 is a large scale vertical section showing 5 in detail the means for adjusting the marginal guides on the paper table.

Fig. 13 is a large scale section on the line 13—13 in Fig. 5.

The numeral 20 in Figs. 1 and 2 designates a 10 suitable desk which may be made of either wood or metal, but it is here shown as made of sheet metal for convenience in description. The desk 20 is of more or less conventional design, having a corner recess 21 to provide a depressed support 15 for the typewriter 22. The typewriting machine here shown is the well known "International" power operated typewriter which was formerly known as the "Electromatic." Since this machine is now well known in the art and its mechanisms have been described in numerous patents, 20 only a very brief general description, such as will enable those skilled in the art to understand the present invention, will be given herein.

The type bars 23 (Fig. 8) are pivotally mounted 25 on the usual wire segment 24 by means of a curved fulcrum wire 25. Each of the type bars is ordinarily locked in the position of Fig. 8 by means of toggle links 26. One of the toggle links, the one which is pivoted to the type bar 23, is 30 connected by a link 27 to a sub-lever 28 pivoted on a fulcrum wire 29. The latter is supported in a frame 30 which is mounted in the framework comprising the base of the machine. Pivotally mounted on rods 31 supported in the framework 35 of the machine are cam units 32 connected by links, like 33, to the sub-levers 28. Each cam unit has a cam 34 which, in the case of those keys 35 (Figs. 1 and 8) which control the operation of the type bars, have two lobes, as in Patent No. 1,777,055. Each key 35 has an arm 35a integral therewith having a slotted connection to a trip lever 36 in the associated cam unit.

When any key 35 is depressed, it operates its trip lever 36 through the arm 35a, allowing the cam 34 of the associated cam unit 32 to rotate a slight amount just sufficient to cause the cam unit to be operatively engaged by the constantly rotating power roller 37. The lobe of the cam 34, in cooperation with the power roller 37, causes 45 the cam unit 32 to be rocked in a clockwise or a counterclockwise direction, depending upon whether the operative cam unit is on the left hand rod 31 or the right hand rod Fig. 8. This causes the associated link 33 to become drawn 50 55

downwardly, thereby rocking the sub-lever 28 in a counterclockwise direction. Through the connections comprising the link 27 and the right hand toggle link 26, the type bar 23 associated with the depressed key is rocked in a clockwise direction to effect an impression of the type on the work sheet.

The carriage comprises end plates 38 (Figs. 2, 7, 8 and 9) integrally joined by a channel-shaped member 39 which is formed with two grooves in which ride the usual antifriction trucks 40 supporting the carriage on the grooved front and rear rails 41, 42, respectively. The platen 43 is rotatably mounted on the carriage by means hereinafter to be described. The usual escapement mechanism is provided comprising a pair of escapement pawls 44 cooperating with the usual escapement rack 45 secured to the under side of the channel-shaped member 39. The escapement mechanism is of the same type disclosed in Patent No. 1,994,544, and is operated by means of a lever 46 pivoted on a bracket 47 secured to the rear rail 42. The lever 46 has a link connection 48 to a universal bar frame 49 having an arcuate portion 49a engaged by the type bars when they effect an impression.

The platen 43 is displaceably mounted on the carriage whereby it may be moved from a typing to a non-typing position for the purpose of permitting a pack of continuous forms with interleaved carbon sheets to be straightened for the purpose of effecting a displacement between the carbon sheets and the forms. The object of this feature is to enable the carbon sheets to be used repeatedly until exhausted. The platen is rotatably mounted on curved arms 50 (Figs. 1, 2, 7 and 8) which are pivotally mounted on studs 51 carried by extension plates 52 secured to the carriage end plates 38. The arms 50 are integrally joined close to the platen by means of a tube 53 which may be welded or brazed or otherwise secured to the arms 50.

The platen supporting arms 50 are latched in the position shown in Figs. 2, 7 and 8 by means of two similar latches 54, 55 secured to the opposite ends of a rod 56 rotatably mounted on the arms 50. The latches 54, 55 cooperate with offset latch lugs 57a (Fig. 7) on latch plates 57 adjustably secured to the end plates 38 of the carriage. Springs 58, anchored to pins carried by the latches 54, 55 and the arms 50, hold the latches 54, 55 in engagement with the lugs 57a, thereby retaining the platen in the typing position shown in Figs. 2, 7 and 8.

In order to disengage the latches to permit raising the platen to its non-typing position there is provided a release lever 59 (Figs. 1, 2 and 7) which is pivotally mounted on rod 56. The lever 59 has a pin 59a (Fig. 7) in the plane of an arm 54a formed in the right hand latch 54. When the lever 59 is raised by hand, that is, rocked clockwise in Fig. 7, the pin 59a causes the latch 54, rod 56, and latch 55 to be rocked clockwise as a unit to disconnect the latches from the latch lugs 57a. With further movement of the lever 59 the platen will be raised to an inoperative position.

The arms 50 supporting the platen 43 may be swung in an arc of approximately sixty degrees and are limited in their clockwise movement (Fig. 7) by means of bent-over lugs 52a formed in the extension plates 52. The arms 50 are yieldingly held in engagement with the lugs 52a by means of torsion springs 60 coiled around the the studs 51 and hooked around the arms 50 and plates

52, respectively. These torsion springs 60 partly counterbalance the weight of the platen and the arms 50 whereby relatively little effort is required to raise the platen to a non-typing position.

For reasons which will be explained herein-after, it is desirable that the platen be locked in its typing position except when the carriage is at a predetermined point. For this purpose the lever 59 has an arm 59b (Figs. 2 and 7) formed with an arcuate slot 59c embracing the stud 51. Secured to the base of the machine at the rear of the carriage is an angle strip 61 which extends parallel with rear rail 42. One flange of angle strip 61 extends vertically and is beveled so as to just barely clear one edge of the arm 59b. The angle strip has a slot 61a formed in the vertical flange in such a position that, when the carriage is centered, as in Fig. 1, the slot 61a will be directly opposite the lever 59b, thereby permitting the arm 59b to pass through the slot. Thus, when the carriage is in a central position, the lever 59 may be rocked in a clockwise direction (Fig. 7) to displace the platen as described above. In any other position of the carriage, however, the vertical flange of the angle strip 61 will block movement of the lever 59 in a clockwise direction and thereby prevent displacing the platen to non-typing position. While the platen is in displaced position, the arm 59b in slot 61a locks the carriage against accidental movement.

The carriage return mechanism has the same general construction as the one described in Patents No. 1,753,450 and No. 1,955,614, but is herein modified to provide for moving the carriage to an intermediate position, namely, the central position mentioned above. Fig. 9 is a perspective view showing parts of the carriage and the carriage return mechanism in more or less diagrammatic form. The carriage return key 62 (see Figs. 1 and 8 also) is pivoted on the left hand rod 31 (Fig. 8) and has an arm 62a controlling a cam unit 63 which is generally similar to the cam units 32 except that the cam unit 63 is provided with a single-lobe cam 64 instead of a double-lobe cam.

The reference numeral 65 in Fig. 9 generally designates a friction clutch mechanism substantially identical with the one described in Patent No. 1,753,450 which, when engaged, causes a tape drum 66 (Fig. 9) to be rotated in such a direction as to wind the carriage return tape 67. The tape 67 passes over a pulley 68 mounted on a fixed part of the framework and thence underneath the channel-shaped member 39 to a pulley 69 mounted on one arm of a bell crank 70. The latter is pivoted on a bracket 71 secured to the top surface of the channel-shaped member 39, the arm of the lever 70 having the pulley 69 extending downwardly through an opening in the channel-shaped member. After passing over the pulley 69 the tape 67 is anchored to the underside of the channel-shaped member 39.

The clutch 65 is controlled by toggle links 72 (Fig. 9) which interconnect a relatively fixed bracket 73 secured to the base of the machine and a clutch operating lever 74. One of the toggle links has an arm 72a connected by a link 75 to the cam unit 63. Whenever the carriage return key 62 is depressed, the cam 64 of the cam unit 63 is caused to operatively engage the power roller 70 77 whereby the latter rotates the cam unit 63 in a clockwise direction (Fig. 8). This causes the link 75 to be drawn downwardly to straighten the toggle comprising links 72 and move the toggle slightly over dead center position. The straight-

ening of the toggle causes the upper end of the lever 74 (Fig. 9) to be moved to the right to engage the clutch 65. An adjustable plate 76 limits the movement of the toggle link 72 beyond the dead center position in which the toggle links are held by means of a spring 77 anchored to the plate 76 and to the upper end of the clutch lever 74.

Cooperating with the arm 72a (Fig. 9) is one arm of a bell crank 78 pivotally mounted on a boss 79 forming part of the framework. The other arm of the bell crank 78 is connected by a link 80 to one arm of a three-armed lever 81 pivotally mounted on a fixed part of the framework. One of the other arms of the lever 81 is connected by a link 82 (see Fig. 6 also) to a trip lever 83 pivotally mounted at 84 on the rear rail 42. The trip lever 83 has an inclined surface 83a designed to act as a cam surface. Secured in the end plates 38 of the carriage is the usual marginal stop rack 85 on which the right and left hand marginal stops 86, 87, respectively, are adjustably mounted.

When the carriage return key 62 is depressed to effect the engagement of the clutch 65 and cause the carriage to be returned, the lever 78 is rocked counterclockwise in Fig. 9. This causes the link 82 to move downwardly and to the right in Fig. 9 or to the left in Fig. 6, thereby rocking the lever 83 in a clockwise direction (Fig. 6). This raises the inclined cam surface 83a into the path of movement of the downwardly projecting part 87a of the left hand marginal stop 87.

Eventually when the carriage is close to the left hand marginal position, the projection 87a will strike the cam surface 83a and rock the lever 83 in a counterclockwise direction (Fig. 6). This causes the link 82 to be drawn to the right in Fig. 6 or upwardly and to the left in Fig. 9, with the result that the lever 78 is rocked in a clockwise direction (Fig. 9) and the arm thereof cooperating with the arm 72a will bend the toggle comprising link 72 and effect disengagement of the clutch 65 in the manner described in Patent 1,753,450.

The carriage is arrested on the left hand marginal position by the engagement of the projection 87a on the left hand marginal stop 87 with a lug 88a formed in the usual tabular lever 88 forming part of the tabulating mechanism. By similar cooperation with the downwardly projecting portion 86a of the right hand marginal stop 86 with the lug 88a the carriage is arrested in the right hand marginal position. The tabulating mechanism is substantially identical with the one described in Patent No. 1,935,436 and, since it is not directly involved herein, will not be described. Insofar as an understanding of the carriage return mechanism is concerned, the tabular lever 88 may be considered as fixed whereby lug 88a remains in the position shown in Figs. 6 and 9.

For the purpose of arresting the carriage in an intermediate position there is provided an intermediate marginal stop 89 (Figs. 6 and 9) which may be adjustably mounted upon marginal stop rack 85 in the same general way as the marginal stops 86, 87. However, the construction of the stop 89 must be slightly different from the stops 86, 87 to avoid the stop 89 striking the lug 88a. For this reason, the stop 89 does not have a downward projection, like 87a, but is merely slotted to provide a plurality of relatively narrow portions designed to enter the interdental spaces on rack 85 and be flush

with the tips of the teeth. The stop 89 has an offset lug 89a (see Fig. 9) having the same function as the projection 87a.

Mounted on the rear rail 42 is a plate 90 formed with a lug 90a on which is pivoted an arm 91. This arm as shown in Figs. 6 and 9, extends horizontally along the top of the rear rail 42 to a point just under the lug 88a and is designed to be raised, that is, rocked counterclockwise in Fig. 6 to bring the right hand end of arm 91 into the path of movement of the lug 89a. When the arm 91 is in the raised position, it forms an obstruction for the carriage by co-operation with the lug 89a to positively arrest the carriage in an intermediate position.

A pin 91a (Fig. 9) on the arm 91 is embraced by a slot in a somewhat similar arm 92 pivotally mounted at 93 (Fig. 6) on a lever 94 which is pivotally mounted on a stud 95 on plate 90. Lever 94 has an offset lug 94a having a hole 20 through which link 82 passes (Fig. 7). The stud 95 (Fig. 9) is embraced by a slot formed in the lever 94 and a spring 96, anchored to the lever 94 and to a relatively fixed part carried by the rear rail 42, holds the lever 94 in the position shown in Fig. 6. The lever 92 is somewhat longer than the arm 91 so as to project to the left of the lug 88a (Fig. 9) or to the right (Fig. 6) several letter spaces distance. Like the lever 91, the right hand end (Fig. 6) of lever 92 will take 30 a position in the path of movement of the lug 89a whenever the lever 91 is raised, owing to the fact that the lever 92 is slidably mounted on the lever 91 by means of the pin 91a. However, due to the fact that arm 92 is somewhat longer than arm 91, 35 the lug 89a will engage the end of arm 92 before said lug strikes the end of arm 91.

The movement of arm 92 relative to arm 91 is utilized to disengage the carriage return clutch. For this purpose, there is mounted upon 40 link 82 (Figs. 6 and 9) a collar 97. When the link 82 is drawn to the left in Fig. 6, as described above, the collar 97 is brought into contact with the lug 94a on lever 94 through which the link 82 passes. When the lug 89a strokes the end of arm 92, said arm is moved longitudinally to the left in Fig. 6, thereby rocking the lever 94 in a counterclockwise direction. This movement, by the engagement of the lug 94a with the collar 97, pushes the link 82 to the right in Fig. 6 and 50 thereby effects disengagement of the carriage return clutch, in the same fashion as the lever 83.

The levers 91, 92 are raised into cooperation with the lug 89a by means of a system of levers and links connected to the carriage return key 55 62. This lever system is shown in Figs. 6 to 9. Secured to a fixed part of the framework underneath the keyboard is a bracket 98 (Fig. 8) on which is pivotally mounted, adjacent the carriage return key, a lever 99. The latter has a pin and slot connection to the carriage return key whereby lever 99 is rocked in a clockwise direction (Fig. 8) whenever the carriage return key is depressed. The lever 99 is connected by means of a horizontal link 100 to a bell crank 101 pivotally mounted on a bracket 102 secured to the framework of the machine. Bell crank 101 is connected by a vertical link 102a with the lever 91.

It is evident that the depression of the carriage return key will result in rocking lever 99 in a clockwise direction (Fig. 8), thereby, through link 100, rocking the lever 101 in a counterclockwise direction and raising the link 102a. With reference to Figs. 6 and 9, the raising of the link 75

102a will elevate both of the arms 91, 92 to bring the free ends thereof into position to be engaged by the lug 89a on the intermediate marginal stop 89.

5 When it is desired to return the carriage to the left hand marginal position preparatory to beginning a new line of typing, the carriage return key 62 is merely depressed and released immediately. Thus, while this operation results in 10 elevating the free ends of the arms 91, 92 as described, the immediate release of the carriage return key permits the arms 91, 92 to fall back to the positions shown in Figs. 6 and 9. When it is desired to centralize the carriage in preparation for lifting the platen to its non-typing position, the carriage return key is held depressed by hand. This causes the arms 91, 92 to be held in elevated position whereby, eventually, lug 89a 15 will strike the end of lever 92 and move it to the left (Fig. 6) or to the right (Fig. 9) and effect the disengagement of the carriage return clutch 65.

In order to absorb the shock resulting when lug 89a strikes the end of arm 91, the plate 90 is 20 slidably mounted on studs 90b, 90c (Fig. 6) the studs projecting through aligned slots in the plate. A heavy coil spring 90d, anchored to a pin 90e carried by plate 90 and to stud 90c, normally holds the plate in the position of Fig. 6 with the left hand ends of the slots engaging 25 the studs 90b, 90c. Obviously this construction permits the plate 90 to yield to the left in Fig. 6 when lug 89a strikes arm 91.

If it should happen that the carriage occupies a position with the lug 89a within a few letter 30 spaces distance from the lug 88a the lug 89a will be over the end of the arm 92 and prevent this arm from rising its full extent. However, the parts are so proportioned that while arm 92 is obstructed from moving more than a small 35 amount, the carriage return key 62 may, nevertheless, be depressed sufficiently to cause engagement of the clutch by releasing the cam unit 63 for operation. This causes a full return of the carriage to the left hand marginal position.

40 The platen 43 is, as usually the case with power operated carriage return mechanisms, automatically line spaced each time the carriage is returned. The means by which the platen is line spaced is described in Patent No. 1,957,322; consequently a detailed description herein will be 45 unnecessary. With reference to Figs. 8 and 9, the lever 70 is rocked with each operation of the carriage return mechanism owing to the fact that the tape 67 passes over the pulley 69 and is anchored to the channel-shaped member 50 55 39 joining the carriage in the plates 38. This operation takes place before the carriage starts to move.

The lever 70 (Fig. 9) has one of its arms 60 slotted to embrace a lug formed in a slide 103 mounted for vertical movement on the left hand carriage end plate 38. This slide carries a pivoted dog 104 which engages the usual line space ratchet 105 (Fig. 1) whereby, each time the slide 103 is drawn downwardly, the platen will be rotated an extent dependent upon the setting of the usual line space control lever 106 (Fig. 9). This lever, as explained in Patent No. 1,957,322, governs the extent of return movement 65 70 of the slide 103 and thereby controls the extent of rotation of the platen.

75 For the purpose of guiding a pack of continuous forms with inter-leaved carbon sheets to the introductory side of the platen, there is provided a paper table 107 (Figs. 1, 7, 8 and 11).

The paper table consists of a partly flat and partly cylindrical plate of sheet metal which has riveted at its ends triangular plates 108 pivotally mounted on the studs 51 which pivotally support the platen arms 50. The edges of the plate 5 107 are formed with longitudinal flanges 107a which stiffen the plate. Springs 109, (Fig. 8) anchored to studs carried by the plates 108 and to ends of the marginal stop rack 85, tend to rock the plates 107, 108 in a counterclockwise 10 direction (Fig. 8). Movement in this direction, however, is limited by studs 110 on the carriage end plates 38.

The paper table 108 is provided with adjustable side guides 111 for cooperation with the 15 edges of the forms to prevent the forms from becoming skewed with reference to the platen during the writing of a line. As shown in Fig. 1, the paper table has two slots 107b extending parallel with the platen. The side guides 111 20 consist of short angle strips to which are welded or otherwise fastened U-shaped pieces 112, the arms of which project through the slots 107b (Fig. 11) and maintain the side guides 111 parallel and at right angles to the platen. However, the U-shaped members 112 fit the slots 107b slightly loosely to permit the side guides 111 25 to be adjusted longitudinally of the paper table 107.

For the purpose of securing the side guides 111 30 in their adjusted positions there are provided thumb screws 113 which loosely pass through holes in the side guides 111 and elements 112 and are threaded into washers 114. To prevent the washers from rotating when the thumb 35 screws 113 are tightened for the purpose of clamping the side guides 111 in adjusted position, each of the washers is milled to provide a rib (Fig. 12) which projects slightly into the slots 107b. The ribs do not fit the slots 107b very 40 tightly, therefore the washers do not interfere with the adjustment of the side guides 111 longitudinally of the paper table 107.

For reasons which will be apparent herein-after, it is desirable that means be provided to 45 relieve the platen and the usual pressure rollers 115, 116 (Figs. 7 and 8) from the tension caused by the weight of the continuous forms hanging from the rear edge of the paper table 107. For this purpose, the side guides 111 are provided 50 with slots 111a (Figs. 7, 8 and 11) which are placed at an angle to the surface of the paper table 107. A rod 116 is loosely mounted at its ends in the slots 111a, the rod being shouldered to form reduced portions which are loosely embraced by the slots. The rod 116 rests on the 55 topmost web of a pack of continuous forms inter-leaved with carbon sheets, as shown in Fig. 1.

During the typing of the forms, the rod 116 does not interfere with the free linespacing 60 movement of the forms toward the introductory side of the platen, owing to the tendency of the forms to lift the rod and move it diagonally away from the paper table 107. However, when the platen is raised and the leading ends of the 65 forms are released, the weight of the forms tends to drag the leading ends of the forms rearwardly over the paper table. This tends to move the rod 116 closer to the paper table 107 whereby 70 the rod, in consequence of its own weight and the friction between the rod and the forms, tends to clamp the forms and prevent the forms from slipping off the paper table.

The feed rollers 115, 116 (Figs. 7 and 8) are mounted upon the paper deflector 117 which 75

curves partly around the platen. The paper deflector 117 is universally pivotally mounted on the end of an arm 118 secured to the middle of a rod 119 journalized in the carriage end plates 38. Directly beneath the free end of arm 118 is located a sleeve 120 screwed into a vertical threaded hole in the channel-shaped member 39. Slidably mounted in the bore of the sleeve 120 is a plunger 121 having a shouldered portion at the upper end projecting loosely through a hole in the arm 118. A compression spring 122, seated on a shoulder on the upper end of the sleeve 120 and bearing against a mushroom-shaped head on the upper end of plunger 121, tends to press the paper table upwardly into engagement with the platen.

Also loosely pivotally mounted upon rod 119 is a form-severing knife and front side guide assembly, one end of which is shown in Fig. 10. This assembly includes two arms 123 (see Figs. 7 and 8 also) each of which is located adjacent one of the carriage end plates 38. The arms 123 project upwardly above and in front of the platen and are rigidly joined together by a rod 124 having a longitudinal slot in which is pressed a serrated knife 125 (see Fig. 1 also). Adjustably slidably mounted on the rod 124 is a pair of front side guides comprising a hub 126 to which is secured an oblong guide plate 127. The hubs 126 are slotted to accommodate the serrated knife 125 which prevents rotation of the side guides upon the rod 124. The side guides 126 are secured in their adjusted positions by means of thumb screws 128 threaded into holes in the hubs. Normally, springs 123a connected to the arms 123 (Fig. 10) and to studs carried by the carriage end plates 38 hold the arms 123 against stop pins 129 also carried by the end plates 38.

The knife 125 normally occupies a position very close to the platen (Fig. 7) and is locked in this position by means of latches 130 (Fig. 10) pivotally mounted on studs 131 carried by the arms 123. Torsion springs 132, hooked around pins carried by the latches 130 and through holes in the pins 131, tend to urge the latches 130 in a clockwise direction (Fig. 10). The lower ends of the latches are hook-shaped, as at 130a in Figs. 7 and 10, so as to partly surround sleeves 133 forming part of the platen assembly. It is evident that the hook-shaped portions 130a of latches 130 prevent rocking the knife and side guide assembly away from the platen (Fig. 10).

When it is desired to manipulate forms wrapped around the platen to correct skewing of the forms or for any other reason, the latches 130 at each end of the carriage may be pressed rearwardly of the machine or to the left in Fig. 10, thereby rocking the hook-shaped portions 130a downwardly far enough to disengage them from the sleeves 133 and permit the knife and side guide assembly to be rocked clockwise (Fig. 10) or counterclockwise (Fig. 7) away from the platen.

A forms carrier is provided for supporting and guiding the pack of continuous forms and rolls of carbon paper. The construction of the forms carrier is shown in Figs. 1 to 5. The forms carrier is pivotally mounted in the desk 20 whereby it may be operated and controlled by means of the operator's feet. Beneath the typewriter 22 the desk is provided with a U-shaped partition plate 134 (Figs. 1 and 2) which provides a space for the operator's legs. Spaced from the side walls of the partition plate 134 are the left hand side panel 135 and the central partition panel 136 of

the desk, providing a narrow vertical space on each side of the space for the operator's feet.

Within the two spaces between the panels 134, 135 and the side walls of the plate 134 is pivotally mounted a framework which includes a pair of angle strips 137 pivotally mounted on the panels 135, 136 by means of studs 138 (Fig. 2) carried by flanged support members 139 secured to the panels 135, 136. The angle strips 137 extend upwardly and rearwardly of the pivots 138 into the relatively large space behind the typewriter formed by the rear wall of the plate 134 and the rear halves of panels 135, 136. This space is open at the bottom and at the rear of the desk, but is covered by a part of the desk top 140a which is hinged at 141 to the remainder of the desk top 140. The hinged portion 140a may be raised and folded back upon the remainder of the desk top 140 to provide access to the forms carrier in replacing the carbon rolls and threading the forms. The partition plate 134 terminates at the level of the corner recess 21 to permit the pack of forms to pass from the forms carrier to the carriage.

At their upper rear ends the angle strips 137 are rigidly joined by an angle strip 142 which may be welded or brazed to the angle strips 137. The angle strips 137 are also joined by means of a tie rod 143. Secured to the angle strips 137 approximately two-thirds of the length of the angle strips from the studs 138 are arms 144 which are bolted securely to the angle strips by means of bolts 145. A second tie rod 146 rigidly inter-connects the links 144.

Normally the framework so far described is held in the elevated position shown in Fig. 2 by means of latches, like 147 (Fig. 2) pivoted on studs 148 carried by flanged elements 149, like 139, secured to the panels 135, 136. These latches engage studs 150 on angle strips 137. In order to secure quiet operation of the latches 147, the studs 150 are provided with short sections of rubber tubing which prevent the clicking noise commonly experienced with latching mechanisms of this type. In order to reduce wear on the sections of tubing, the latches 147 are provided with brackets 147a which are wide enough to reduce the indentation of the rubber which would occur if the relatively thin edges of the latches were permitted to rub on the rubber.

The latches 147 are released by means of a foot treadle 151 (Fig. 2) which is formed from a narrow strip of sheet metal with marginal stiffening flanges and pivoted at its corners to two arms 152 which in turn are pivoted on studs 153 carried by flanged members 154 secured to the panels 135, 136. Secured to the angle strips 137 at the pivot point 138 are arms 155 connected by means of links 156 to the arms 152. The links 156 are extended beyond the point of pivoting to the arms 152 and to these links are attached spring anchor rods 157. Springs 158 anchored to the rods 157 and hook bolts 159 counterbalance a very large share of the weight of the parts pivoted on the studs 138. The hook bolts 159 are located in holes 65 on brackets 150 secured to the panels 135, 136.

The springs 158 are adjusted in tension so as to permit the framework, of which the members 137 are part, to drop of its own weight when latches 147 are released, but counterbalance enough of the weight to make it relatively easy for the operator to restore the forms carrier to the position of Fig. 2. Links 161 connected to the corners of the foot pedal 151 and to the latches 147, make it possible to release the latches by rotating

the pedal 151 in a clockwise direction relative to the arms 152 by pressure of the operator's feet on the rear edge of the pedal. Springs 162 connected to the links 161 and to fixed parts of the desk hold the latches 147 against flanged stop members 163 secured to the panels 135, 136.

Adjustably mounted on the tie rods 143, 146 are two carbon roll carriers 165 best illustrated in Figs. 3 to 5 on each of which is mounted a roll 10 of carbon paper 164 by means hereinafter to be described. The carbon roll carriers 165 are formed from flat sheet metal plates provided with narrow stiffening flanges along each edge. One of the flanges 165a of each carrier has holes 15 through which loosely pass the rods 143, 146 and while the other flange has two hubs riveted to the flanges 165a through which the rods 143, 146 pass. Thumb screws 167 secured into holes in the hubs 166 provide a means whereby the carbon roll carriers 165 may be adjustably secured in any desired position along the rods 143, 146.

Secured to the top face of each carbon roll carrier 165 is a pair of brackets 168, 169 in which the carbon rolls 164 are rotatably mounted. 25 As shown in Fig. 5, the brackets 168 are single armed and provided with pivoted spring pressed latches 168a which cooperate with the axles 170 on which the carbon rolls 164 are mounted, the axles resting in a notch formed in the bracket 168. The brackets 169 are double-armed and rotatably support stub shafts 171 (Figs. 4 and 13) to which are pinned collars 172, each collar being located between the arms of the bracket 169 as shown in Fig. 13. The stub shafts 171 are provided with enlarged portions 171a having transverse slots 171b. Each stub shaft 171 also has a bore 171c adapted to receive a reduced portion formed in the end of the axle 170. The axle 170 is also transversely slotted to form a key or spline 171d which fits in the transverse slot 171b in the stub shaft 171 whereby the axle 170 and the stub shaft 171 are coupled together. Cooperating with each collar 172 (Figs. 5 and 13) are two brake members 173 which are pivoted on a common pin 174 mounted on the arms 45 of the bracket 169. At their free ends the brake members 173 are interconnected by a spring 175 and are curved so as to partly conform to the curvature of the collar 172. Thus the carbon rolls 164 mounted on the rods 170 are frictionally restrained from rotation.

Each of the carbon roll carriers 165 (Figs. 3 to 5) is provided with a pair of posts 176 located adjacent the edges of the carbon strips unwound 55 from the rolls 164. At this point it is desired to explain that each roll 164 comprises a plurality of superposed webs impregnated with carbon material. Mounted on the posts 176 are the carbon turning members 177 which consist in each case of rods bent in the form of a triangle to provide a carbon sheet turning bar 177a and a separating bar 177b, with the turning bar 177a forming an angle of forty-five degrees with the separating bar 177b.

65 At the ends of the separating bar 177b there is secured to the bends in the carbon turning members 177 grooved bushings 177c, the bushings being welded or brazed to the carbon turning member. The bushings 177c fit loosely over the 70 posts 176 whereby the carbon turning members may be stacked upon the posts, as shown in Figs. 4 and 5, and clamped in place by means of thumb screws 178. The bushings 177c are of such thickness and the posts 176 are so designed that the 75 carbon turning members may be stacked in an

interleaved relationship best shown in Figs. 4 and 5, whereby any given carbon turning member mounted on one pair of posts 176 extends between a similar pair of such members located on the opposite pair of posts 176. This construction is necessary when fanfolded continuous forms are used, owing to the fact that such forms have longitudinal folds and it is necessary that the carbon turning members project into these folds and wholly supported at the open side of 10 the fold.

The front and rear or shorter marginal flanges 165b (Figs. 3 to 5) of the carbon roll carriers 165 support side guides 179 which are in the form of angular brackets attached to the ends of the 15 flanges 165b by means of screws 180. Slots in the side guides 179 permit the guides 179 to be adjusted transversely of the pack of continuous forms to guide the edges thereof.

With reference to Figs. 3 to 5, the individual 20 plies of carbon webs 164a leading from the rolls 164 are separated by means of the separating bars 177b of the form guides 177. From the separating bars 177b the individual webs pass in 25 between the open sides of the folds of the forms which are designated 181 in Figs. 1 and 3, and led over the turning bars 177a which deflect the webs parallel with the edges of the forms 181 as shown in dotted lines in Fig. 3. In Fig. 3 the continuous forms are shown as of the well known 30 fanfold type in which the forms are made from a relatively wide strip folded longitudinally a plurality of times so as to have alternate folds cooperating with the ends of alternate carbon turning members 177, with the carbon webs 164a 35 introduced at the open sides of the folds. Since it is well known in the art how to load a forms carrier employing carbon rolls in a billing machine utilizing fanfold forms, this operation will not be described herein.

In order to relieve the friction of the forms 40 upon the front and rear edges of the carbon carriers 165 from which the forms hang, there is provided a pair of guide rollers 182 having the ends thereof reduced and loosely seated in 45 holes carried by the side guides 179. These rods are not shown in Figs. 4 and 5 in order to avoid confusion, but appear in Figs. 1 and 3. The front side guides 179, that is, those nearest the typewriter with reference to Fig. 2, are provided 50 with two of the guide rods 182 between which the pack of forms passes, whereby, when the forms carrier is in the position of Fig. 2 and the slack in the forms there shown has been completely taken up, spreading of the top webs of the forms, which would tend to lift the guides 177, 55 is prevented.

The forms are placed in a box 183 (Fig. 2) 60 secured to the lower edges of the panels 134, 136 whereby the forms are supported as close to the floor as possible so as to allow ample space for the forms carrier to oscillate. In order to limit movement of the forms carrier and reduce shock due to its stoppage, there are secured to the ends of the arms 137 rubber cushions 184 like the feet 65 usually attached to typewriter bases. These cushions strike flat rubber pads 185 cemented or otherwise secured to the bottom of the box near the side walls. If desired, the box 183 may be provided with adjustable side plates 186 slidably mounted in slots in the floor of the box in much 70 the same fashion as the side guides 177 for the purpose of holding the forms in the box in alignment with the forms carrier.

The operation of the machine will now be explained in detail. 75

It will be assumed that the forms carrier occupies the position shown in Fig. 2 during the typing of the forms which may be, as shown in this figure, of the fanfold accordion-folded type in which the forms are folded transversely and disposed in zig-zag relation in the box 183 beneath the end of the forms carrier. Fig. 2 shows the machine in readiness to type the first set of forms and it will be noted that there is quite an appreciable slack portion or loop 181a between the paper table 107 and the form guides 182 nearest the typewriter. As the typing of the forms proceeds this slack is gradually taken up whereby, when the last line of the form has been typed, there may be very little slack remaining.

The next operation is to effect a displacement between the carbon sheets and the forms to shift the active portions of the carbon sheets from cooperation with the first set of forms to cooperation with the second set of forms. At this point it is desired to state that in accordance with custom in this art, the leading edges of the carbon sheets may terminate a short distance from the leading edges of the first forms or are so designed that the leading edges of the first set of forms may be grasped by the operator's fingers without grasping the carbon sheets. Unless the carriage happens to be in the central position, it will be impossible, as pointed out above, to raise the platen to its non-typing position. In order to align the platen with respect to the forms carrier, as in Fig. 1, the operator may depress the carriage return key and hold it in depressed position. This causes the carriage to be returned to the intermediate position (Fig. 1) in which the slot 61a (Fig. 7) registers with the arm 59b of lever 59. With the carriage now in the position of Fig. 1, the operator grasps the leading edges of the first forms with one hand and, while still holding the forms, raises the platen to non-typing position by lifting the lever 59 as described above. While holding the corners of the forms with both hands, the operator next presses down upon the pedal 151 (Fig. 2) in such fashion as to rock the pedal clockwise (Fig. 2) and thereby disengage the latches 147 from the studs 150. This permits the forms carrier to swing in a clockwise direction of its own weight, thereby drawing the forms straight. This operation tends to lift the rod 116 (Figs. 1 and 7) away from the paper table 107 and at the same time draws the carbon sheets and forms downwardly and to the right in Fig. 2 to pull the forms into a straight stretch extending diagonally downwardly from left to right (Fig. 2) between the operator's fingers and the rods 182 on the forms carrier. If desired, this movement of the forms carrier can be used to effect all, or nearly all, of the displacing movement of the carbon sheets to the next set of forms.

The operator next draws the forms upwardly and to the left (Fig. 2) to effect the displacing movement, or complete it if the downward movement of the forms carrier is utilized to partly effect the displacing movement. In order to gauge the amount of movement of the carbon sheets relative to the forms, a suitable leading edge gauge of conventional form may be used. However, since the forms are usually so thin that the carbon sheet easily can be seen through the forms, the operator can, by watching the forms and controlling the movement of the forms carrier, or, by pulling the forms upwardly, gauge the displacement by eye.

The precise method followed in any given case

will be discretionary with the operator and will depend largely on the length of the forms. Thus with short forms, requiring only a short displacement of the carbon sheets, the forms carrier might move too far and shift the carbon sheets too much when the downward movement of the forms carrier takes place. In this case the operator may allow the forms carrier to pull the forms downwardly until the forms carrier stops and then effect the entire displacing operation by pulling on the forms with the hands. When long forms are used, the operator, after raising the platen, may pull the forms into a straight stretch and then allow the forms carrier to shift the carbon sheets to the next set of forms while firmly holding the leading edges of the first set of forms.

After the shifting of the carbon sheets takes place, the forms carrier may be raised to latching position (Fig. 2) by pushing the pedal 151 to the right. The platen is now lowered; the line of perforations between the first two sets of forms is brought into registry with the knife 125 by turning the usual platen rotating knobs, and the first set of forms severed. The machine is now in readiness to type the second set of forms.

After a certain number of forms have been typed, the working portions of the carbon sheets will become exhausted of transfer material and new working portions must be brought to working position. This is done, during the carbon shifting operation, by grasping both the forms and carbon sheets and unwinding sufficient lengths of carbon sheets from rolls 164 to provide new working portions. The used portions are severed from the new portions when the last typed forms are severed after the carbon shifting operation. The braking effect exerted on the carbon rolls 164 is adjusted to normally hold the carbon rolls against rotation when the carbon sheets are shifted but to permit the rolls to turn when both the forms and carbon sheets are pulled by hand.

While there has been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It is the intention therefore to be limited only as indicated by the scope of the following claims.

What is claimed is as follows:

1. In a continuous billing machine, the combination of a carriage having a platen displaceable from a forms typing to a carbon stripping position; a forms carrier movably mounted behind the carriage independently thereof, said forms carrier having means to anchor carbon sheets interleaved with the forms; means to align the carriage with the forms carrier and means to prevent displacement of the platen except when the carriage is aligned with the forms carrier.
2. In a continuous billing machine, the combination with a carriage, a platen displaceably mounted in the carriage for movement from a typing to a carbon stripping position, means to effect a displacement of the platen to carbon stripping position, a forms carrier mounted independently of the carriage for supporting and guiding forms interleaved with carbon sheets to the platen, means to operate the forms carrier

- to produce a slack loop in the forms between the platen and forms carrier to permit free movement of the carriage, means to move the carriage into alignment with the forms carrier as a preliminary to effecting a displacement between the forms and the carbon sheets, and means mounted independently of the carriage and cooperating with the platen displacing means to prevent displacement of the platen except when the carriage and forms carrier are aligned. 5
3. In a continuous billing machine, the combination with a carriage, a platen displaceably mounted in the carriage for movement from a typing to a carbon stripping position, and means operative when the platen is displaced to carbon stripping position to lock the carriage against movement. 10
4. In a continuous billing machine, the combination with a carriage, a platen displaceably mounted in the carriage for movement from a typing to a carbon stripping position, a forms carrier movably mounted behind the carriage for supporting and guiding a pack of forms with interleaved carbons to the platen, said forms carrier being movable away from the platen as an incident to displacement of the carbon sheets from one set of forms to another set of forms, means to hold the forms carrier in a forward position, means controlled by the operator for moving the forms carrier, and means operated by the last-named means for releasing the holding means. 15
5. In a continuous billing machine, a carriage having a platen displaceable from a writing to a carbon stripping position, a forms carrier comprising a frame pivoted for oscillatory movement toward and from the carriage and having means to support and guide a pack of continuous forms with interleaved carbon sheets wrapped around the platen, said pack extending from the platen to and over said forms carrier with a slack loop between said platen and said carrier, means to latch the forms carrier in a forward position to maintain the slack loop, a pedal for controlling the movement of the forms carrier away from its forward position and for restoring the carrier to said position, and connections between the latching means and pedal for controlling the latch. 20
6. In a continuous billing machine, a carriage, a forms carrier mounted in the rear of the carriage and relative to which the carriage is movable in writing lines, said forms being interleaved with carbons; a platen displaceably mounted in the carriage for movement from a typing to a carbon stripping position, and means to prevent displacement of the platen to carbon stripping position except when the carriage is in a position favorable for stripping carbons. 25
7. In a continuous billing machine, a carriage, a platen movably mounted in the carriage for displacement from a typing to a carbon stripping position, means to hold the platen in typing position, means to release the holding means, and means cooperating with the releasing means and adapted to prevent operation of the releasing means except when the carriage is in a predetermined position. 30
8. In a continuous billing machine, a carriage having a platen and means to movably mount the platen in the carriage for displacement from a typing to a carbon stripping position, a platen displacing device, and means cooperating with the platen displacing device for preventing movement of the carriage when the platen is displaced to carbon stripping position. 35
9. In a continuous billing machine, a carriage having a platen displaceable from a forms typing to a carbon stripping position, manual means to displace the platen, and means cooperating with the manual means and including a locking bar disposed parallel with the path of movement of the carriage for locking the displacing means against operation in all positions of the carriage except a predetermined position, said locking bar being so shaped that, when the platen is displaced in the predetermined position of the carriage, the carriage is locked against movement. 40
10. In a continuous billing machine, the combination with a carriage and a platen displaceably mounted in the carriage for movement from a typing to a carbon stripping position; a forms carrying device comprising a pivoted frame having means to support and guide continuous forms, means to support rolls of transfer webs alongside the margins of the forms, and means to guide the transfer webs between the forms and turn the webs longitudinally of the forms, said forms carrying device being movable toward and away from the platen for the purpose of producing a slack loop in the pack comprising the forms and transfer webs between the platen and forms carrying device, said device being mounted independently of the carriage so as to remain stationary when the carriage moves; releasable means to hold the forms carrying device in a forward position to maintain said loop, and means to operate both the forms carrying device and the holding means, said operating means being operable in one way to first release the holding means and in another and different way to control the movements of said device toward and away from the slack loop maintaining position. 45
11. In a continuous billing machine, a carriage and a platen movably mounted on the carriage for displacement from a typing to a carbon stripping position, a forms carrier and carbon strip anchoring device mounted for movement toward and away from the platen to retract the carbon sheets, means to hold the forms carrier device at one of its limits of movement, and means operable in two different ways to operate the forms carrier device and the holding means, respectively. 50
12. In a continuous billing machine, the combination of a carriage, a platen movably mounted in the carriage for displacement from a typing to a carbon stripping position, means including a manual lever for displacing the platen, a forms carrier mounted independently of the carriage so as to be immovable with the carriage, and a slotted bar cooperating with the manual lever to prevent displacement of the platen, the slot in said bar permitting operation of said lever only when the platen is aligned with the forms carrier. 55
13. In a continuous billing machine, a carriage, a platen mounted in the carriage, a forms carrier having a fixed mounting so as to be immovable with the carriage in its letter-spacing movements, key controlled power operated means to align the carriage with the forms carrier, and means to lock the carriage in alignment with the forms carrier. 60
14. In a continuous billing machine, a carriage, a platen movably mounted in the carriage for displacement from a writing to a carbon stripping position, a forms carrier pivotally mounted independently of the carriage for move- 65
- 70
- 75

ment toward and away from the carriage, platen displacing means, key controlled power operated means to align the platen and forms carrier, and means cooperating with the platen displacing means for preventing displacement of the platen unless the latter is aligned with the forms carried and operative to lock the carriage against movement when the platen is displaced.

15. In a continuous billing machine, a carriage, a platen movably mounted in the carriage, for displacement from a typing to a carbon stripping position, releasable means to hold the platen in typing position, and a locking device for preventing release of the holding means except when the carriage is in a predetermined position.

CHARLES H. BEIDERBECKE.
